HYDRODYNAMIC MACHINE

Walter Ferris, Milwaukee, Wis., assignor to The Oilgear Company, Milwaukee, Wis., a corporation of Wisconsin

Application May 25, 1944, Serial No. 537,346

18 Claims. (Cl. 103—120)

1

This invention relates to hydrodynamic machines of the type having a plurality of vanes slidably fitted in slots formed substantially radially in a rotor, a spacer ring arranged around the rotor and spaced therefrom, cheek plates arranged upon opposite ends of the rotor and held in spaced relation by the spacer ring, and a vane track arranged around the rotor inside of the spacer ring and including a plurality of bridges which cooperate with the vanes to divide the space between the rotor and the spacer ring into high pressure and low pressure chambers.

Such a machine ordinarily has two diametrically opposed sealing bridges which are arranged close to the rotor and two working bridges which are spaced 90° from the sealing bridges and are spaced from the rotor when the machine is performing useful work at which time the outer ends of the vanes ride along the vane track and pass through the low pressure and high pressure chambers successively. If the rotor is rotated, the vanes passing across the working bridges will transfer liquid from the low pressure chambers to the high pressure chambers and the machine will function as a pump. If motive liquid is supplied to the high pressure chambers, it will act upon the outer end portions of the vanes in contact with the working bridges and rotate the rotor, thereby causing the machine to function as a motor. If the working bridges are moved toward or from the rotor, the displacement of the machine will be varied and, if the outer bridges are moved inward close to the rotor and the inner bridges are moved outward, the machine will be reversed to thereby reverse the direction of flow if the machine is functioning as a pump or to reverse the direction of rotation if the machine is functioning as a motor.

In prior machines of this type, the high pressure and low pressure chambers communicate with an external circuit through ports which extend axially from the chambers but the liquid pumped by or required to operate a machine of large volumetric capacity cannot flow through axial ports without excessive head losses as will presently be explained.

The outer ends of vanes passing through the high pressure chambers are subjected to the pressure therein. In order to prevent this pressure from moving those vanes inward out of engagement with the vane track, one of the cheek plates is provided in its inner face with vane slot ports which are spaced radially inward

2

from the high pressure and low pressure chambers and with which the inner ends of the vane slots register successively as the rotor rotates, and the vane slots that are radially inward from the high pressure chambers are supplied with liquid at a pressure at least as high as the pressure in the high pressure chambers.

In prior machines, the vane slot ports that are radially inward from the high pressure chambers communicate through holes in the cheek plate with grooves which are formed in the outer face of the cheek plate and are connected to a source of high pressure liquid. The outer face of the cheek plate is in contact with a flat surface which closes the open sides of the grooves but the pressure causes liquid to seep from the grooves and form a film between the cheek plate and the flat surface. The pressure extends into this film so that the liquid in the groove and in the film exerts sufficient force upon the cheek plate to deflect it against the end of the rotor and cause it to impose a drag or brake load thereon.

The present invention has an object to provide a hydrodynamic machine of the sliding vane type which is free from the objectionable characteristics mentioned above.

Another object is to provide a vane type hydrodynamic machine with hydraulic means for adjusting the bridges thereof and means for supplying liquid to said hydraulic means first at a low pressure and automatically increasing the pressure in response to the pressure in said machine exceeding a given value.

Another object is to provide a vane type hydrodynamic machine with a vane track having a bridge which constitutes the piston of a servomotor for adjusting that bridge.

Another object is to provide means to positively limit the movement of a vane track bridge.

Another object is to provide a vane type hydrodynamic machine that may be made to have a large volumetric capacity.

Another object is to provide a vane type hydrodynamic machine with radial ports so that it may have a large volumetric capacity.

Another object is to provide a vane type hydrodynamic machine with novel means for effecting reversal thereof.

Another object is to provide a cheek plate that will not be deflected by the liquid supplied to the vane slot ports therein.

Another object is to provide a hydrodynamic machine with means for supplying liquid at a low pressure to the vane slot ports to initially urge

the vanes against the vane track and means to automatically increase the pressure of the liquid in response to the pressure at the outer ends of the vanes exceeding a given value.

These and other objects and advantages are obtained in the embodiment of the invention shown in part in detail and in part schematically in the accompanying drawings in which the views are as follows:

Fig. 1 is a central longitudinal section through a machine in which the invention is embodied, the view being taken on the line 1—1 of Fig. 2 and the lower part of the casing being broken away in order to show the working parts on a larger scale.

Fig. 2 is a transverse section taken across the end of the rotor as indicated by the line 2—2 of Fig. 1.

Fig. 3 is an enlarged perspective view of one of the vane track sections shown in Fig. 2.

Fig. 4 is a view taken in the plane of the line 4—4 of Fig. 2 but drawn to a larger scale and showing the means for connecting the vane track sections to the bridges and the means for moving the bridges radially outward.

Fig. 5 is a view drawn to the same scale as Fig. 4 and illustrating the mechanism for moving a bridge toward the rotor and for controlling the movement of the bridge away from the rotor, the view being taken on the longitudinal centerline of the machine in the same plane as Fig. 1 and as indicated by the line 5—5 of Fig. 6 but it shows the bridge in a position different from that shown in Figs. 1 and 4.

Fig. 6 is a fragmentary section taken on the line 6—6 of Fig. 2 and showing the arrangement of the springs for urging a bridge radially outward, the view being drawn to the same scale as Fig. 5.

Fig. 7 is a view taken approximately on the irregular line 7—7 of Fig. 8 and showing the radial ports through which liquid flows to and from the rotor.

Fig. 8 is a transverse section taken on the line 8—8 of Fig. 1 and illustrating the passages through which liquid flows to and from the ports shown in Fig. 7.

Fig. 9 is a diagrammatic view illustrating the hydraulic circuits of the machine.

The machine shown in the drawings is intended to function as a pump and it will be described as such but the machine will function as a motor if it is supplied with motive liquid, and it is to be understood that the present invention is in no way limited to a pump.

As shown, the pump has its mechanism arranged within a casing 1 having formed therein a cylindrical recess 2 which is larger in diameter at its front than at its rear to receive an end head 3 which closes recess 2 and has a peripheral flange 4 formed thereon and extending around the inner periphery of the enlarged part of recess 2. Flange 4 has the same inner diameter as the rear part of recess 2, and an upper portion of flange 4 is cut away to accommodate a control mechanism as will presently be explained.

Recess 2 contains a spacer ring 5 which is fitted in the rear part thereof and within the rear part of flange 4. A rotor 6 is arranged inside of spacer ring 5 and provided with a plurality of substantially radial vane slots 7 each of which has a vane 8 slidably fitted therein.

When the machine is performing useful work, each vane moves outward and draws liquid into its slot during one part of a revolution of the

rotor and it moves inward and expels liquid from its slot during the succeeding part of a revolution of the rotor. The vane slots cannot be extended radially inward but very little beyond the innermost positions of the vanes without dangerously weakening the rotor. Consequently, if each vane slot had the same width throughout its length, the flow of liquid to the inner end of a vane would be greatly restricted when the vane was in its innermost position. In the present instance, the rotor is considerably longer than the rotors of the prior machines and, in order to provide unrestricted flow of liquid to the inner end of each vane throughout the entire length thereof, the inner end of each vane slot 7 is enlarged in the form of a circular bore as shown in Figs. 2 and 7.

Spacer ring 5 and rotor 6 are arranged between a cheek plate 9, which is fitted in the rear part of recess 2 and engages the rear wall thereof, and a cheek plate 10 which is fitted within flange 4 and engages a gear pump cover plate 11 which is also arranged within flange 4 and engages the inner face of end head 3. The cheek plates, spacer ring, gear pump cover plate and end head are rigidly clamped together by a plurality of bolts 12 which extend therethrough and are threaded into the rear part of casing 1, spacer ring 5 being just enough longer than rotor 6 to provide running clearances between the ends of the rotor and the adjacent faces of the cheek plates.

Rotor 6 is splined upon and driven by a drive shaft 16 which extends through cheek plates 9 and 10 and through cover plate 11 and is journaled in suitable bearings carried by casing 1 and end head 3 respectively. Drive shaft 16 also drives a gear pump having one gear 17 splined upon shaft 16 and its other gear 18 meshing with gear 17 and journaled upon a stub shaft 19 which is fixed in end head 3. Gears 17 and 18 are arranged in a suitable pumping chamber 20 which is formed in end head 3 and has its open side closed by cover plate 11. Pumping chamber 20 communicates with an external circuit through passages which do not appear in Fig. 1 but are shown schematically in Fig. 9.

The outer ends of vanes 8 engage a smooth track surface formed upon the inner periphery of an endless vane track of the type described and claimed in application Serial No. 530,425 filed April 10th, 1944 by Walter Ferris. The vane track consists primarily of four identical bridges 24, 24^a, 24^b and 24^c, which are equally spaced around rotor 6 as shown in Fig. 2, and four identical track sections 25, 25^a, 25^b and 25^c which are arranged between adjacent bridges and pivotally connected thereto. The track sections are extensible and the bridges are adjustable toward and from the rotor to vary the displacement of the pump, the track surface on each track section is concave, the track surface on each bridge is concave intermediate its ends for a distance at least as great as the angular distance between the outer ends of two adjacent vanes and it is convex adjacent each of its ends so that it is tangent to the concave surfaces on the adjacent track sections in all positions of the bridges, and the ends of the track sections and bridges are so shaped as to provide an unbroken path for the vanes as explained in said application.

As shown in Fig. 3, each track section includes two parts 26 and 27 which are telescopically connected to each other by two guide segments

28 and 29 arranged upon opposite sides thereof and each segment is preferably fixed to one of the parts as by means of a pin 30. Each track section has a concave track surface formed upon its inner face and, as explained in application Serial No. 530,425, segments 28 and 29 are telescopically connected to parts 26 and 27 in such a manner that they hold the track surfaces thereon in circumferential alinement with each other while permitting parts 26 and 27 to move toward and from each other to vary the length of the vane track, the adjacent ends of parts 26 and 27 being complementary to each other and extending diagonally inward from opposite sides to provide an unbroken path for the vanes in all positions of parts 26 and 27.

In order to provide the smoothest possible radial movements of the vanes, the track sections should be pivotally connected to adjacent bridges at points spaced as far radially outward as may be conveniently possible within the available space. To this end, each track section part 26 has two posts 31 and 32 rigidly secured thereto, each track section part 27 has two posts 33 and 34 rigidly secured thereto, and the outer ends of the posts are provided with suitable holes so that the posts may be pivotally connected to the bridges as will presently be explained.

Bridges 24, 24^a, 24^b and 24^c are arranged, respectively, in recesses 35, 35^a, 35^b and 35^c which are formed in spacer ring 5 as shown in Fig. 2. Each bridge is closely fitted between the sides of its recess and between check plates 9 and 10, so that the bridges and the vanes in contact therewith divide the space between the periphery of rotor 6 and the inner periphery of spacer ring 5 into alternate intake and discharge chambers. In prior pumps of this character, the intake and discharge chambers are connected to opposite sides of an external circuit through ports which extend axially therefrom through one of the check plates. This arrangement is entirely satisfactory in pumps of the sizes ordinarily used but it is not at all satisfactory in large pumps for the reason that an increase in capacity does not result in a proportional increase in the area of axial ports.

The volumetric capacity of a vane pump is determined by the peripheral speed of its rotor, the diameter of its rotor, the length or thickness of its rotor and its stroke or the distance that the vanes extend beyond the periphery of the rotor. Since pumps are ordinarily run at the highest practical rotary speed and since increasing the diameter would increase the rubbing speed (that is, the speed at which the ends of the vanes slide along the vane track), increasing either the rotary speed or increasing the diameter of the rotor beyond the diameter necessary to provide sufficient metal between the shaft bore and the vane slots is not a practical way to provide large increases in volumetric capacity. Even if the diameter of the rotor could be readily increased, an increase in rotor diameter would result in only a proportional increase in displacement but the weight of the pump would increase in accordance with the square of the diameter.

If the stroke of the pump should be increased enough to cause the pump to have a large displacement, the vanes in contact with the pumping bridges would extend so far from the periphery of the rotor that vanes of proper thickness would be bent or broken by the high pressure created by the pump, the thickness of the vanes

being limited due to the fact that, when a vane is passing across a pumping bridge, high pressure acts upon the full area of the inner end of the vane but acts upon only about one half of the area of the outer end of the vane so that the pressure acting upon the differential area forces the vane against the bridge and, if the vane should be too thick, it would be urged against the bridge with such force that excessive wear of the bridge and vane would result and the efficiency of the pump would be reduced. Consequently, increasing the stroke to obtain a large displacement is impractical.

Increasing the length of the rotor causes a proportional increase in the displacement of the pump but the space between the periphery of the rotor and the vane track remains unchanged so that the area of axial ports cannot be increased but the flow through the port must increase in proportion to the increase in displacement. Consequently, liquid cannot flow through an axial port to and from the space between the rotor and the vane track of a large capacity pump without excessive head losses. In fact, a large pump could not draw liquid from an adjacent reservoir through an axial port fast enough to keep the space between its rotor and vane track completely filled with liquid.

The pump illustrated in the drawings is adapted to be made in large sizes, that is, it is capable of having a large volumetric capacity. In order to avoid the head losses incident to axial ports, each of track sections 25, 25^a, 25^b and 25^c is provided with a radial port or opening 40 as shown in Fig. 3. The ports 40 in track sections 25, 25^a, 25^b and 25^c communicate, respectively, with four ports 41, 41^a, 41^b and 41^c which, as shown in Figs. 2 and 7, are formed in spacer ring 5 and in cheek plate 9. As shown in Figs. 7 and 8, ports 41^a and 41^c communicate, respectively, through two passages 42^a and 42^c with an annular passage 46 which is formed in casing 1 around the hub of shaft 16 and has two branches 47 and 48. Ports 41 and 41^b communicate, respectively, through two passages 42 and 42^b with an arcuate passage 43 which is spaced radially outward from passage 46 and has two branches 44 and 45. Branch passages 44 and 47 connect the pump to an external circuit and branch passages 45 and 48 connect the pump to an automatic suction valve as will presently be explained.

As previously explained, each vane track section is pivotally connected to adjacent bridges by means of the posts 31, 32, 33 and 34 shown in Fig. 3. The two posts fixed to each track section part 26 or 27 extend into two recesses four of which are formed in each bridge, and both of these posts are journaled upon a pivot pin or shaft which extends through the bridge and the cheek plates. For example and as shown in Fig. 4, the posts 31 and 32 which are fixed to part 26 of track section 25 extend, respectively, into two recesses 51 and 52 which are formed in bridge 24, and both of posts 31 and 32 are journaled upon a long pivot pin 53 which extends through the bridge and has its opposite ends arranged in two recesses 54 and 55 which are formed in cheek plates 9 and 10 respectively. One end of track section 25 is similarly connected to the other side of bridge 24 and the other ends of track sections 25 and 25^c and both ends of track sections 25^a and 25^b are similarly connected to the other bridges.

75 Pivot pin 53 extends through two bushings 56

and 57 which are fixed in bridge 24 and extend from opposite sides thereof into recesses 54 and 55 to provide stops to engage the inner walls of recesses 54 and 55 and positively limit the inward movement of the bridge and thereby prevent the vane track from being urged against the periphery of the rotor by the displacement varying mechanism to be presently described.

Pin 53 provides an anchor for two springs 58 and 59 arranged, respectively, in two recesses 60 and 61 which are formed in cheek plates 9 and 10, respectively, and extend radially inward from the peripheries thereof into communication with recesses 54 and 55 respectively. Springs 58 and 59 have their inner ends attached to pin 53 and their outer ends attached, respectively, to two pins 62 and 63 which are arranged within suitable slots formed in the cheek plates and extending across recesses 60 and 61 respectively. Pins 62 and 63 bear against the inner ends of their slots and enable springs 58 and 59 to urge bridge 24 outward. The other end of track section 25 and both ends of the other track sections are similarly connected to the adjacent bridges so that the inward movement of each bridge is limited by stops 56 and 57 and, as shown in Fig. 6, each bridge is urged outward by two springs 58 and two springs 59.

As previously explained, bridges 24, 24^a, 24^b and 24^c are closely fitted, respectively in recesses 35, 35^a, 35^b and 35^c and between cheek plates 9 and 10. The arrangement is such that motive liquid may be directed to and from the outer ends of the recesses to enable each bridge to function as the piston and its recess to function as the cylinder of a servo-motor for moving that bridge toward the rotor. The flow of liquid to and from recesses 35, 35^a, 35^b and 35^c is controlled, respectively, by four follow-up valves 67, 67^a, 67^b and 67^c.

Since the flow control means for all four bridges are identical, a description of one will suffice for all. For example and as shown in Fig. 5, bridge 24 is controlled by a valve 67 which is fitted in a bore 68 formed in bridge 24 and in spacer ring 5. Valve 67 controls communication between a supply passage 69 and a passage 70 and between passage 70 and a discharge passage 71 all of which are formed in bridge 24. Passage 70 connects the outer end of recess 35 to bore 68 at a point intermediate the ends thereof. Passage 69 communicates with bore 68 at a point spaced radially inward from passage 70 and it is constantly supplied with motive liquid as will presently be explained. Passage 71 communicates with bore 68 at a point spaced radially outward from passage 70 and it connects bore 68 to a passage 72 extending through cheek plate 9 into communication with an annular passage 73 which is formed in the periphery of cheek plate 9 and in the rear face of cheek plate 9 adjacent to periphery thereof.

Passage 73 is connected to drain through a passage 74 having a check valve 75 arranged therein. Likewise and as shown in Fig. 1, gear pump cover plate 11 has an annular passage 76 formed in its periphery and connected to drain through a passage 77 having a check valve 78 arranged therein. Check valves 75 and 78 offer a low resistance, such as 10 lbs. per sq. in., to the discharge of liquid therethrough to thereby keep casing 1 filled with liquid and to provide lubrication for the bearings.

Valve 67 (Fig. 5) has formed therein a camber which is exactly the same length as the distance between the adjacent edges of passages

69 and 71 and so located that valve 67 normally blocks communication between passages 69, 70 and 71.

Valve 67 is adapted to be moved inward mechanically, as will presently be explained and, when it moves inward, it opens passage 69 to permit liquid to flow therefrom through bore 68 and passage 70 to the outer end of cylinder 35 and move bridge 24 inward, and bridge 24 in moving inward will tend to close passage 69 as fast as valve 67 opens it so that movement of bridge 24 ceases substantially as soon as movement of valve 67 ceases.

Valve 67 is urged outward by a spring 79 arranged in the inner end of bore 68 and in a recess formed in the inner end of valve 67. When valve 67 is permitted to move outward, it opens passage 71 and then the forces exerted upon bridge 24 by the pressures in the pump and by springs 58 and 59 will move bridge 24 outward and cause it to expel liquid from the outer end of recess 35 through passage 70, bore 68 and passages 71, 72, 73 and 74 to drain. Bridge 24 in moving outward will tend to close passage 71 as fast as valve 67 opens it so that movement of bridge 24 ceases substantially as soon as movement of valve 67 ceases.

When valve 67 is stationary, bridge 24 is held stationary for the reason that liquid cannot flow into recess 35 to move bridge 24 inward and the liquid trapped in recess 35 prevents bridge 24 from being moved outward by the forces exerted thereon. If bridge 24 should move in one direction or the other from an adjusted position, it would open passage 69 or passage 71 just as soon as it started to move and opening one or the other of those passages would cause bridge 24 to be returned to its adjusted position before it had moved an appreciable distance therefrom.

Valves 67, 67^a, 67^b and 67^c are urged outward by their springs 79 into engagement with a cam ring 80 which is arranged around spacer ring 5 and rotatably supported within the enlarged part of recess 2 by an annular roller bearing 81 as shown in Figs. 1 and 2, axial movement of cam ring 80 being prevented by flange 4 and the shoulder formed by enlarging the front part of recess 2.

The inner periphery of cam ring 80 constitutes a cam track which is concentric with rotor 6 except at four places where it is recessed to form four cam surfaces 82, 82^a, 82^b and 82^c for effecting operation of valves 67, 67^a, 67^b and 67^c respectively. The parts are so proportioned that a valve in engagement with a concentric portion of the cam track on cam ring 80 will be held in its innermost position and a valve in engagement with one of the cam surfaces will have been moved outward from its innermost position a distance proportional to the distance the end of the valve moved along the cam surface from the adjacent concentric portion of the cam track.

Since each bridge moves with its valve and occupies the same relative position as its valve as previously explained, a bridge will be in its innermost position or close to rotor 6 when its valve is in engagement with a concentric portion of the cam track and it will move outward away from rotor 6 when one of the cam surfaces moves into alignment with its valve and permits the valve to move outward.

The four cam surfaces are so located that only two valves can engage cam surfaces at the same time but all four valves can engage concentric portions of the cam track at the same time. When cam ring 80 is in its neutral position, all

four valves are in engagement with concentric portions of the cam track so that all four bridges are in their innermost positions and pump displacement is zero.

When cam ring 80 is rotated from its neutral position clockwise in respect to Fig. 2, valves 67^a and 67^c will ride along the concentric portions of the cam track so that bridges 24^a and 24^c are held in their innermost positions but valves 67^b and 67^d will ride, respectively, onto cam surfaces 82 and 82^b which will permit valves 67^b and 67^d to move outward and cause bridges 24^b and 24^d to move outward.

Holding bridges 24^a and 24^c close to the rotor and moving bridges 24^b and 24^d away from the rotor, causes the pump to discharge liquid in one direction at a rate dependent upon the distances that bridges 24^b and 24^d are moved from their innermost or zero displacement positions. For example, if rotor 6 is rotated in the direction of the arrow, the vanes passing across bridge 24^b will transfer liquid from port 41 to port 41^c and the vanes passing across bridge 24^d will transfer liquid from port 41^b to port 41^a so that the pump draws liquid through ports 41^a and 41^c and discharges it through ports 41^b and 41^d. If cam ring 80 is rotated far enough to permit valves 67^b and 67^d to move outward until they have caused bridges 24^b and 24^d to stall against the outer ends of recesses 35 and 35^b as shown in Fig. 2, pump displacement will be maximum and the pump will deliver liquid at its maximum rate through ports 41^a and 41^c.

When cam ring 80 is rotated counterclockwise from the position shown in Fig. 2, cam surfaces 82 and 82^b will force valves 67^b and 67^d inward which will cause bridges 24^b and 24^d to move inward and reduce pump displacement until cam ring 80 reaches its neutral position at which time bridges 24^b and 24^d will have been moved to their innermost positions and pump displacement will be zero.

Continued rotation of cam ring 80 will bring cam surfaces 82^a and 82^c into alignment with valves 67^a and 67^c which will then move outward and cause bridges 24^a and 24^c to move outward but valves 67^b and 67^d will remain in contact with concentric portions of the cam track so that bridges 24^b and 24^d are held in their innermost positions. With bridges 24^b and 24^d in their innermost positions and bridges 24^a and 24^c moved outward, the pump will function as previously explained but it will deliver liquid in the opposite direction at a rate dependent upon the distances bridges 24^a and 24^c are moved from their innermost positions.

Cam ring 80 is rotated through a pin 83 (Figs. 1 and 2) which connects it to a link 84 and to the connecting rod 85 of a piston 86 fitted in a cylinder 87 which is formed in or connected to casing 1 and to which motive liquid is constantly supplied through a channel 88 from a suitable source. For example, channel 88 may be connected to gear pump 17-18 as shown in Fig. 9.

Link 84 connects pin 83 to one end of a lever 90 the other end of which is pivotally connected to casing 1 by a shaft 91. Lever 90 is provided intermediate its ends with a roller 92 to engage the inner end of a sleeve 93 having a piston 94 arranged thereon and closely fitted in a cylinder 95.

Piston 94 and cylinder 95 constitute a servo-motor which is controlled by a rotary valve 96 journaled in the sleeve 93 and in the head of cylinder 95 and provided on its outer end with means, such as a lever 97 for rotating it. Liq-

uid for operating servo-motor 94-95 flows to and from cylinder 95 through a port 98 extending through the wall of sleeve 93 and normally arranged between two spiral grooves 99 and 100 which are formed in the periphery of valve 96. Groove 99 is drained into casing 1 through at least one hole 101 formed in the inner end of sleeve 93. Groove 100 communicates with a passage 102 formed within valve 96 and communicating with a port 103 which is formed in the head of cylinder 95 around valve 96 and connected by a channel 104 to a supply of liquid so that groove 100 is constantly supplied with motive liquid. For example, channel 104 may be connected to gear pump 17-18 as shown in Fig. 9.

When valve 96 is rotated counterclockwise as viewed from the right end of Fig. 2, groove 100 will move into registry with port 98 and then liquid will flow from channel 104 through port 103, passage 102, groove 100 and port 98 into cylinder 95 and cause piston 94 to move toward the left and swing lever 90 counterclockwise upon shaft 91. Lever 90 will move link 84 and pin 83 toward the left to thereby rotate cam ring 80 counterclockwise in respect to Fig. 2 and to also move connecting rod 85 and piston 86 toward the left, the effective area of piston 94 being enough greater than that of piston 86 to enable piston 94 to move toward the left when cylinders 87 and 95 are both supplied with liquid at the same pressure.

Piston 94 in moving toward the left will move port 98 with it and tend to close communication between groove 100 and port 98 as fast as rotation of valve 96 opens communication therebetween. Consequently, cam ring 80 will be rotated through an angular distance exactly proportional to the angular distance through which valve 96 is rotated.

When valve 96 is rotated clockwise as viewed from the right end of Fig. 2, groove 99 will move into registry with port 98 and then the liquid constantly supplied to cylinder 87 will cause piston 86 to move connecting rod 85, pin 83 and link 84 toward the right, pin 83 will rotate cam ring 80 clockwise in respect to Fig. 2, link 84 will swing lever 90 upon shaft 91, and roller 92 will move piston 94 toward the right and cause it to eject liquid from cylinder 95 through port 98, groove 99 and hole 101 into casing 1. Piston 94 in moving toward the right will move port 98 with it and tend to close communication between groove 99 and port 98 as fast as rotation of valve 96 opens communication therebetween. Consequently, cam ring 80 will be rotated through an angular distance exactly proportional to the angular distance through which valve 96 is rotated.

Channels 88 and 104 may be connected to one branch of a supply channel 108 (Fig. 9) into which gear pump 17-18 discharges liquid drawn from a reservoir 109. The liquid discharged by gear pump 17-18 in excess of requirements is exhausted through a relief valve 110 which enables gear pump 17-18 to maintain a constant pressure, such as 85 lbs. per sq. in., in channel 108. The outlet of relief valve 110 is connected by a channel 111 to the inlet of a relief valve 112 through which liquid in excess of requirements is exhausted into reservoir 109 and which is adapted to open at a pressure lower than the pressure required to open relief valve 110 so that it does not effect the pressure in channel 108. Relief valve 112 also resists the discharge of

11

liquid from a valve bore 113 having an automatic suction valve 114 fitted therein. Bore 113 has two annular grooves or ports 115 and 116 formed in its wall and spaced from its opposite ends, and it communicates at a point intermediate ports 115 and 116 with channel 111 and with a check valve 117 which permits liquid to be drawn into bore 113 from reservoir 109 but prevents discharge of liquid from bore 113 into reservoir 109 except through relief valve 112.

As previously explained and as shown in Fig. 8, main ports 41 and 41^b communicate with a passage 43 having two branches 44 and 45 for connection to an external circuit and to a suction valve respectively, and main ports 41^a and 41^c communicate with a passage 46 having two branches 47 and 48 for connection to an external circuit and to the suction valve respectively. These passages are represented schematically in Fig. 9 by channels which bear the same reference numerals as the passages in Fig. 8.

As shown in Fig. 9, main ports 41 and 41^b communicate with a channel 43 having a branch 44, which is adapted to be connected to an external circuit, and a branch 45 which is connected to the port 116 of the automatic suction valve and provided with an auxiliary branch 45^a which communicates with the right end of bore 113. Main ports 41^a and 41^c communicate with a channel 46 having a branch 47, which is adapted to be connected to an external circuit, and a branch 48 which is connected to the port 115 of the automatic suction valve and provided with an auxiliary branch 48^a which communicates with the left end of bore 113.

The arrangement is such that, when the pump discharges liquid into ports 41^a and 41^c as previously explained, the liquid discharged by the pump will flow through channels 46 and 47 to the external circuit since it cannot flow into reservoir 109 for the reason that at this time valve 114 is blocking port 115. The liquid returned from the external circuit flows through channels 44 and 43 and ports 41 and 41^b to the interior of the pump. If the liquid returned from the circuit is in excess of pump requirements, the excess liquid is exhausted through channel 45, bore 113 and relief valve 112 into reservoir 109. If the liquid returned from the circuit is insufficient, a part or all of the liquid discharged by gear pump 17-18 into channel 111 will flow therefrom through bore 113, channels 45 and 43 and ports 41 and 41^b to the interior of the pump. If the liquid returned from the circuit and the liquid discharged by gear pump 17-18 into channel 111 do not together provide sufficient liquid for pump requirements, the pump will draw liquid from reservoir 109 through check valve 117, valve bore 113, channels 45 and 43 and ports 41 and 41^b into the pump.

When the pump is reversed so that it discharges into ports 41 and 41^b, the liquid discharged by the pump will tend to flow through channels 43 and 45 and valve bore 113 into reservoir 109 but check valve 117 prevents flow into reservoir 109 except through relief valve 112 which resists the discharge of liquid therethrough and thereby causes pump pressure to rise and liquid to flow through branch 45^a to the right end of bore 113 and cause valve 114 to shift toward the left and block port 116 so that the liquid discharged by the pump cannot enter bore 113 but must flow into the external circuit.

Liquid returned from the circuit flows to the pump through channels 47 and 46 and ports 41^a and 41^c, any excess is discharged through re-

12

lief valve 112 and any deficiency is made up by gear pump 17-18 and also if necessary by liquid drawn through check valve 117. When the pump is again reversed so that it discharges into channel 46, relief valve 112 will cause pressure to rise and liquid to flow through branch 48^a to the left end of bore 113 and cause valve 114 to shift toward the right to the position shown and block port 115 so that the pump cannot discharge through relief valve 112.

When the pump is running idle and when the pressure created by it is less than gear pump pressure, bridges 24 and 24^b or bridges 24^a and 24^c may be moved inward by liquid supplied to recesses 35 and 35^b or recesses 35^a and 35^c from gear pump 17-18 at the pressure determined by relief valve 110 which pressure is high enough to enable the gear pump liquid to exert sufficient force upon the outer ends of the bridges to move the bridges inward against the outward forces exerted thereon by springs 58 and 59 and by the low pressure acting upon the inner ends of the bridges.

If relief valve 110 should be adjusted to enable gear pump 17-18 to deliver liquid to the recesses at a pressure high enough to effect operation of the bridges when main pump pressure was maximum, excessive power loss and heating of the liquid would result. Therefore, the bridges are operated by liquid at gear pump pressure or main pump pressure whichever is the higher.

As shown schematically in Fig. 9, gear pump supply channel 108 is connected to a distributing channel 121 through a check valve 122 which permits liquid to flow from channel 108 into channel 121 but prevents flow in the opposite direction. Channel 121 is connected to channel 43 through a check valve 123 and to channel 46 through a check valve 124 so that the pressure can extend from channel 43 or channel 46 into channel 121 but liquid cannot flow from channel 121 into either channel 43 or 46, and distributing channel 121 is connected to the supply passage 69 (Fig. 5) in each of bridges 24, 24^a, 24^b and 24^c.

Distributing channel 121 may be an internal passage formed within the pump structure but for the purpose of illustration it has been shown in Fig. 9 as an external channel and as being connected to the supply passages in bridges 24, 24^a, 24^b and 24^c through channels 125, 125^a, 125^b and 125^c respectively. As shown in Figs. 1 and 5 channel 125 has its inner portion arranged radially within cheek plate 10 with its inner end in communication with the passage 69 in bridge 24 and its outer portion extending axially through cover plate 11 and end head 3 so that it passes around gear pump 17-18. As shown in Fig. 1, channel 125^b extends axially through end head 3, cover plate 11 and cheek plate 10 into communication with the passage 69 in bridge 24^b. Channels 125^a and 125^c are the same as channel 125^b and are indicated schematically in Fig. 9 but do not appear in the other figures.

It has previously been explained that in a vane type hydrodynamic machine the inner ends of the vane slots register successively with a plurality of vane slot ports which are formed in the inner face of one of its cheek plates and that liquid may flow to and from the vane slot ports through channels which communicate therewith and through which pressure may be transmitted for urging the vanes outward against the vane track.

Since such an arrangement of vane slot ports

is well known, it has not been completely illustrated in detail but has been shown schematically in Fig. 9 which is diagrammatic with the central portion thereof representing a view looking from the left end of spacer ring 5 toward the right in respect to Fig. 1 with rotor 6 removed to expose the central portion of the rear face of cheek plate 10, rotor 6 being indicated by a dot and dash circle.

As shown in Fig. 9, cheek plate 10 has formed in its rear or inner face four arcuate vane slot ports 131, 132, 133 and 134, which are spaced radially inward from ports 41, 41^a, 41^b and 41^c respectively, and four short vane slots ports 135, 136, 137 and 138 which are spaced radially inward from bridges 24, 24^a, 24^b and 24^c respectively. Vane slot ports 131 and 132 also appear in Fig. 7 and vane slot ports 135 and 137 also appear in Fig. 1.

During rotation of the rotor, each vane moves radially outward and draws liquid into its slot from a vane slot port as its outer end travels along the vane track from a sealing bridge to a working bridge, the outer end portion of the vane transfers liquid from an intake port to a discharge port as it passes across the working bridge, and the vane moves radially inward and ejects liquid from its slot into a vane slot port as its outer end travels along the vane track from the working bridge to the adjacent sealing bridge.

Vanes passing across the working bridge thus pump a principal volume of liquid and the vanes in moving radially pump a secondary volume of liquid which is proportional to the principal volume and equal to a substantial portion thereof. For example, the pump shown is capable of pumping 32,000 cu. in. per minute due to the passage of its vanes across the working bridges and approximately 3000 cu. in. per minute due to the radial movement of its vanes, thus making a total discharge of approximately 35,000 cu. in. per minute.

When the machine is used as a pump, the rotor is rotated at high speed and it is ordinarily only necessary to hydrostatically balance the vanes as the centrifugal force is ordinarily sufficient to hold the vanes in contact with the vane track but, when the rotor is rotated at slow speed and when the machine is functioning as a motor and is started under a load, the vanes must be positively urged against the vane track.

In order to hold the outer ends of the vanes in contact with the track surfaces on the bridges, the vane slot ports which are spaced radially inward from the bridges are supplied with liquid first at a low pressure and then at pump pressure, a pressure higher than pump pressure being unnecessary as the outer end portions of a vane have pump pressure on one side thereof and a low or negative pressure on the other side thereof during almost its entire journey across the track surface on a bridge so that pump pressure acts upon only a portion of the outer end area of the vane.

The vane slot ports spaced inward from the bridges may be connected to each other by a channel formed in the pump structure and that channel connected to suitable sources of pressure but for the purpose of illustration vane slot ports 135, 136, 137 and 138 have been shown in Fig. 9 as being connected, respectively, to channels 125, 125^a, 125^b and 125^c by channels 140, 141, 142 and 143 respectively. Channels 140 and 142 also appear in Fig. 1.

In order to utilize the liquid pumped by the radial movement of the vanes and to provide pressure for urging the vanes outward against the vane track, the vane slot ports spaced inward from the intake ports are connected to each other, to the gear pump and to one side of the external circuit and the vane slot ports spaced inward from the discharge ports are connected to each other, to the gear pump and to the other side of the external circuit.

As shown in Fig. 9, vane slot ports 131 and 133 are connected to each other by a channel 144 which is formed in cheek plate 10, they are also connected through a channel 145 and a check valve 146 to gear pump supply channel 108 and are also connected through a channel 147, a check valve 148 and a resistance valve 149 to channel 13, vane slot ports 132 and 134 are connected to each other by a channel 150 which is formed in cheek plate 10, they are also connected through a channel 151 and a check valve 152 to gear pump supply channel 108 and are also connected through a channel 153, a check valve 154 and a resistance valve 155 to channel 46.

Check valves 146 and 154 permit liquid to flow from the external circuit into the vane slot ports connected thereto but they prevent flow from those ports into the external circuit except through resistance valves 149 and 155. Check valves 146 and 152 prevent liquid from flowing from the vane slots connected thereto into channel 108 but they permit liquid to flow from channel 108 to the inner ends of the outward moving vanes whenever, as is usually the case, the liquid delivered to the inner ends of those vanes from the external circuit is insufficient to keep their slots filled with liquid.

Resistance valve 149 has two ports 160 and 161 formed in its casing 162 and connected, respectively, to channels 43 and 147. Communication between ports 160 and 161 is controlled by a valve 163 having a piston 164 arranged upon its inner end and fitted in a bore 165 formed in casing 162. Port 160 communicates with the inner part 45 of bore 165 through a duct 166 which extends axially through valve 163 and piston 164 so that whatever pressure is prevailing in port 160 will act upon the inner or large face of piston 164 and urge valve 163 toward its seat, valve 163 being initially urged against its seat by a light spring 167 arranged in the inner part of bore 165.

Port 161 communicates with the outer end of bore 165 through a slot 168 which is formed in 55 the periphery of valve 163 so that whatever pressure is prevailing in port 161 will act upon the outer or small face of piston 164 and tend to move valve 163 away from its seat to open communication between ports 160 and 161. The parts are so proportioned and the tension of spring 167 is such that the drop in pressure across resistance valve 149 is somewhat greater than the pressure created by gear pump 71—73. For example, resistance valve 149 may be adapted to 60 open in response to the pressure in port 161 becoming 100 lbs. per sq. in. greater than the pressure in port 160. Since resistance valve 155 is identical to resistance valve 149, its parts have been indicated by the same reference numerals 70 that are applied to corresponding parts of resistance valve 149 and a description thereof is deemed unnecessary.

The arrangement is such that, when the parts are in the positions shown and rotor 6 is rotated in the direction of the arrow so that the

15

pump is discharging through ports 41^a and 41^b into channel 46 , liquid returned from the circuit will flow through channel 43 to ports 41 and 41^b , liquid may flow into vane slot ports 131 and 133 from channel 43 through check valve 148 and channels 147 and 144 and from channel 108 through check valve 146 and channels 145 and 144 to keep the slots of the outward moving vanes filled with liquid at gear pump pressure so that the outward moving vanes have their inner ends subjected to gear pump pressure which holds the outer ends thereof in engagement with the vane track.

As the vanes pass from a working bridge to a sealing bridge, they will be forced inward by the vane track and the outer ends of the vanes will be subjected to the pressure created by the pump which pressure if unopposed would move the vanes inward out of engagement with the vane track. However, the inward moving vanes will eject liquid from their slots into vane slot ports 132 and 134 from which this liquid can escape, due to check valves 152 and 154 , only through resistance valve 155 which prevents the discharge of liquid therethrough until the inward moving vanes have created a pressure which is enough higher than pump pressure to enable the liquid acting upon the small area of piston 164 to exert a force which exceeds the total force exerted upon the large area of piston 164 by the pump pressure and by spring 167 . Then resistance valve 155 will open and permit the liquid pumped due to radial movement of the vanes to flow into channel 46 to augment the liquid pumped due to rotary movement of the vanes, and the pressure required to open resistance valve 155 will act upon the inner ends of the inward moving vanes and positively hold the outer ends of those vanes in engagement with the vane track.

When bridges 24 and 24^b are moved to their innermost positions and bridges 24^a and 24^c are moved outward, the pump will function in the above described manner except that the flow to and from the main and vane slot ports will be reversed. That is, the pump will discharge through main ports 41 and 41^b into channel 43 , main ports 41^a and 41^c will be supplied with liquid through channel 46 , vane slot ports 132 and 134 will be supplied with liquid through one or both of check valves 152 and 154 , the vanes passing across ports 41 and 41^b will be forced inward by the vane track and will eject liquid from their slots into vane slot ports 131 and 133 , and escape of liquid from vane slot ports 131 and 133 will be prevented by check valves 146 and 148 except through resistance valve 149 which will cause the inward moving vanes to create sufficient pressure to hold the outer ends of those vanes in engagement with the vane track.

In prior hydrodynamic machines of the sliding vane type, the vane slot ports formed in the inner face of a cheek plate were customarily connected to channels which were formed in the opposite face of the cheek plate and closed on their open sides by the flat surface that constituted the bearing for the cheek plate. The pressure in these channels caused liquid to seep between the outer face of the cheek plate and the supporting flat surface and form a film therebetween, the pressure in the high pressure channels would extend into the film adjacent those channels, and the pressure in the high pressure channels and in the adjacent film would cause the cheek plate to yield inward toward the rotor. Since there is only a running clearance between the inner face

16

of a cheek plate and the end of the rotor, a very slight yielding of the cheek plate would cause it to engage the end of the rotor and impose a drag or brake load thereon and thereby not only decrease the efficiency of the machine but also cause excessive wear of the parts with the result that the machine would have excessive slip at low pressures.

In order to overcome the above objectionable characteristics of prior machines, the present invention provides a cheek plate having channels formed in the interior thereof. For example, channels 140 , 141 , 142 , 143 , 144 and 150 may be formed in the interior of cheek plate 10 as indicated in Fig. 1 in which channels 149 and 142 appear and as indicated in Fig. 7 in which channels 144 and 150 appear. With the vane slot ports connected to a source of pressure liquid through channels formed in the interior of a cheek plate, the pressure in those channels cannot force the cheek plate against the end of the rotor and cause loss of efficiency and excessive wear. This feature is not claimed herein but is claimed in a divisional application Serial No. 39,866, filed July 21, 1948.

It is sometimes possible to connect ports in the inner face of a cheek plate to a source of pressure liquid through channels which extend axially outward from those ports. If such an axial channel is located so far radially inward from the spacer ring that high pressure in the channel might cause liquid to seep between the outer face of a cheek plate and its supporting surface and force a film therebetween so that pressure could extend into the film and deflect the cheek plate against the end of the rotor, deflection of the cheek plate may be prevented by forming a drain passage in the cheek plate or in its supporting surface around the channel and connecting the drain passage to drain as indicated in Fig. 1, in which a drain passage 170 is formed in cover plate 11 around channel 125^b and connected to drain passage 77 .

The hydrodynamic machine disclosed herein may be modified in various ways and adapted to various uses without departing from the scope of the invention which is hereby claimed as follows:

1. In a hydrodynamic machine having high and low pressure ports and a vane track including a plurality of bridges each of which is arranged between a high pressure port and a low pressure port, two bridges constituting a pair and at least one bridge of a pair being adjustable to vary the displacement of said machine, the combination with an adjustable bridge of hydraulic means for adjusting the same, said hydraulic means including a pressure chamber, a source of constant pressure liquid, means for supplying liquid from said source to said chamber to energize said hydraulic means, and means for supplying liquid at a pressure higher than said constant pressure to said chamber in response to the pressure in said high pressure port exceeding said constant pressure.

2. In a hydrodynamic machine having high and low pressure ports and a vane track including a plurality of bridges each of which is arranged between a high pressure port and a low pressure port, two bridges constituting a pair and at least one bridge of a pair being adjustable to vary the displacement of said machine, the combination with an adjustable bridge of hydraulic means for adjusting the same, a source of constant pressure liquid, means including a

follow-up valve for supplying liquid from said source to said hydraulic means to energize the same, and means for supplying liquid to said valve at the pressure prevailing in said high pressure port in response to said pressure exceeding said constant pressure.

3. In a hydrodynamic machine having high and low pressure ports, a rotor, and cheek plates arranged upon opposite ends of said rotor, the combination of a recessed spacer ring arranged around said rotor to hold said cheek plates in spaced relation, an articulated vane track arranged around said rotor and within said spacer ring and including a plurality of bridges each of which is arranged between a high pressure port and a low pressure port, two bridges constituting a pair and at least one bridge of a pair being adjustable to vary the displacement of said machine, said adjustable bridge being fitted in a recess in said spacer ring to form therewith a servo-motor, means for supplying liquid to said servo-motor to energize the same including a valve for controlling the flow of liquid to and from said servo-motor, and means for adjusting said valve to effect operation of said servo-motor and thereby effect adjustment of said bridge.

4. In a hydrodynamic machine having high and low pressure ports, a rotor, and cheek plates arranged upon opposite ends of said rotor, the combination of a recessed spacer ring arranged around said rotor to hold said cheek plates in spaced relation, a vane track arranged around said rotor and within said spacer ring and including a plurality of bridges each of which is arranged between a high pressure port and a low pressure port, two bridges constituting a pair and at least one bridge of a pair being adjustable to vary the displacement of said machine, said adjustable bridge being fitted in a recess in said spacer ring to form therewith a servo-motor, means for supplying liquid at a constant pressure to said servo-motor to energize the same including a valve for controlling the flow of liquid to and from said servo-motor, means for adjusting said valve to effect operation of said servo-motor and thereby effect adjustment of said bridge, and means for supplying liquid at a pressure higher than said constant pressure to said valve in response to the pressure in said high pressure port exceeding said constant pressure.

5. In a hydrodynamic machine having high and low pressure ports, a rotor, and cheek plates arranged upon opposite ends of said rotor, the combination of a recessed spacer ring arranged around said rotor to hold said cheek plates in spaced relation, an articulated vane track arranged around said rotor and within said spacer ring and including a plurality of bridges each of which is arranged between a high pressure port and a low pressure port, two bridges constituting a pair and at least one bridge of a pair being adjustable to vary the displacement of said machine, said adjustable bridge being fitted in a recess in said spacer ring to function as a piston and having formed therein a valve bore and passages leading from said bore for the flow of liquid through said bore to and from said recess, means for supplying liquid to said bore, a valve fitted in said bore for controlling the flow of liquid to and from said recess, and means for adjusting said valve.

6. In a hydrodynamic machine having high and low pressure ports, a rotor, and cheek plates

arranged upon opposite ends of said rotor, the combination of a recessed spacer ring arranged around said rotor to hold said cheek plates in spaced relation, an articulated vane track arranged around said rotor and within said spacer ring and including a plurality of bridges each of which is arranged between a high pressure port and a low pressure port, two bridges constituting a pair and at least one bridge of a pair being adjustable to vary the displacement of said machine, said adjustable bridge being fitted in a recess in said spacer ring to function as a piston and having formed therein a valve bore and passages leading from said bore for the flow of liquid through said bore to and from said recess, means for supplying liquid to said bore, a valve fitted in said bore for controlling the flow of liquid to and from said recess, means for adjusting said valve, and means yieldingly retaining said valve in engagement with said valve adjusting means to enable said valve and bore to function as a follow-up valve and thereby prevent said bridge from wandering from the position determined by said valve adjusting means.

7. In a hydrodynamic machine having a rotor, the combination of a vane track arranged around said rotor and including a plurality of bridges all of which are movable toward and from said rotor to vary the displacement of said machine and to reverse said machine if it is a motor or to reverse the flow if the machine is a pump, two adjacent bridges constituting a pair and one bridge of said pair being closer to the rotor than the other bridge when the machine is performing useful work, means for moving each bridge toward and from said rotor, and means for operating the moving means for either bridge of a pair without effecting operation of the moving means for the other bridge of that pair so that either bridge of a pair may be caused to move toward or from said rotor while the other bridge remains stationary.

8. In a hydrodynamic machine having a rotor, the combination of a vane track arranged around said rotor and including a plurality of bridges which are movable toward and from said rotor to vary the displacement of said machine and to reverse said machine if it is a motor or to reverse the flow if the machine is a pump, two bridges constituting a pair and one bridge of each pair being closer to the rotor than the other bridge when the machine is performing useful work, the bridges closer to the rotor constituting one set and the other bridges constituting a second set, means for moving each bridge toward and from said rotor, and means for operating all of said moving means and adapted to operate the moving means for either set of bridges simultaneously without effecting operation of the moving means for the other set of bridges.

9. In a hydrodynamic machine having a rotor, the combination of a vane track arranged around said rotor and including a plurality of bridges which are movable toward and from said rotor to vary the displacement of said machine and to reverse said machine if it is a motor or to reverse the flow if the machine is a pump, two bridges constituting a pair and one bridge of each pair being closer to the rotor than the other bridge when the machine is performing useful work, the bridges closer to the rotor constituting one set and the other bridges constituting a second set, a servo-motor for effecting movement of each bridge toward and from said rotor, means for supplying liquid to each servo-motor to energize

the same including a valve for controlling the flow of liquid to and from each servo-motor, and means for operating said valves and adapted to operate the valves of either set of bridges simultaneously without effecting operation of the valves of the other set of bridges.

10. In a hydrodynamic machine having a rotor and two cheek plates arranged upon opposite ends of said rotor, the combination of a recessed spacer ring arranged around said rotor to hold said cheek plates in spaced relation, a vane track arranged around said rotor and within said spacer ring and including a plurality of bridges each of which is fitted in a recess in said spacer ring and forms therewith a servo-motor, two bridges constituting a pair and one bridge of each pair being closer to the rotor than the other bridge when the machine is performing useful work, the bridges closer to the rotor constituting one set and the other bridges constituting a second set, means for supplying liquid to each servo-motor to energize the same including a valve for controlling the flow of liquid to and from each servo-motor, and means for operating said valves and adapted to operate the valves of either set of bridges simultaneously without effecting operation of the valves of the other set of bridges.

11. In a hydrodynamic machine having a rotor, the combination of a vane track arranged around said rotor and including a plurality of bridges which are movable toward and from said rotor to vary the displacement of said machine and to reverse said machine if it is a motor or to reverse the flow if the machine is a pump, means for moving each bridge toward and from said rotor, a cam ring arranged around said bridges concentric with said rotor, individual cam tracks one for each bridge arranged upon said cam ring and adapted to effect operation of said moving means to cause said bridges to move toward and from their innermost positions during angular adjustment of said cam ring, cam tracks arranged upon and concentric with said ring joining said individual tracks and adapted to hold said moving means in such positions that the bridges controlled thereby are held in their innermost positions, said cam tracks being so located that said individual tracks control alternate moving means only and said concentric tracks control all of said moving means in one position of said ring and control alternate moving means in all other positions of said ring, and means for adjusting said ring to various angular positions.

12. In a hydrodynamic machine having a rotor, the combination of a vane track arranged around said rotor and including a plurality of bridges which are movable toward and from said rotor to vary the displacement of said machine and to reverse said machine if it is a motor or to reverse the flow if the machine is a pump, means for moving each bridge toward and from said rotor, a cam ring arranged around said bridges concentric with said rotor, individual cam tracks one for each bridge arranged upon said cam ring and adapted to effect operation of said moving means to cause said bridges to move toward and from their innermost positions during angular adjustment of said cam ring, cam tracks arranged upon and concentric with said ring joining said individual tracks and adapted to hold said moving means in such positions that the bridges controlled thereby are held in their innermost positions, said cam tracks being so located that said individual tracks control alternate moving means only and said concentric tracks control all of

said moving means in one position of said ring and control alternate moving means in all other positions of said ring, hydraulic means for adjusting said ring to various angular positions, and means for supplying liquid to said hydraulic means including a follow-up valve to control said hydraulic means and enable it to move said ring to and hold it in an adjusted position.

13. In a hydrodynamic machine having a rotor, 10 the combination of a vane track arranged around said rotor and including a plurality of bridges which are movable toward and from said rotor to vary the displacement of said machine and to reverse said machine if it is a motor or to reverse 15 the flow if the machine is a pump, a servo-motor for effecting movement of each bridge toward and from said rotor, means for supplying liquid to each servo-motor to energize the same including a valve for controlling the flow of liquid to and from each servo-motor, a cam ring arranged around said bridges concentric with said rotor, individual cam tracks one for each valve arranged upon said cam ring and adapted to effect operation of said valves to cause said servo-motors to move said bridges toward and from their innermost positions during angular adjustment of said cam ring, cam tracks arranged upon and concentric with said ring joining said individual tracks and adapted to hold said valves in 20 such positions that the servo-motors controlled thereby hold said bridges in their innermost positions, said cam tracks being so located that said individual tracks control alternate valves only and said concentric tracks control all of said 25 valves in one position of said ring and control alternate valves in all other positions of said ring, and means for adjusting said ring to various angular positions.

14. In a hydrodynamic machine having a rotor, 40 the combination of a vane track arranged around said rotor and including a plurality of bridges which are movable toward and from said rotor to vary the displacement of said machine and to reverse said machine if it is a motor or to reverse 45 the flow if the machine is a pump, a servo-motor for effecting movement of each bridge toward and from said rotor, means for supplying liquid to each servo-motor to energize the same including a valve for controlling the flow of liquid to and from each servo-motor, a cam ring arranged around said bridges concentric with said rotor, individual cam tracks one for each valve arranged upon said cam ring and adapted to effect operation of said valves to cause said servo-motors to move said bridges toward and from their innermost positions during angular adjustment of said cam ring, cam tracks arranged upon and concentric with said ring joining said individual tracks and adapted to hold said valves in 50 such positions that the servo-motors controlled thereby hold said bridges in their innermost positions, said cam tracks being so located that said individual tracks control alternate valves only and said concentric tracks control all of said 55 valves in one position of said ring and control alternate valves in all other positions of said ring, hydraulic means for adjusting said ring to various angular positions, and means for supplying liquid to said hydraulic means including a follow-up valve to control said hydraulic means and enable it to move said ring to and hold it in an adjusted position.

15. In a hydrodynamic machine having a rotor, a vane track arranged around said rotor and including a plurality of bridges at least one of

which is movable toward and from said rotor to vary the displacement of said machine, the combination with a movable bridge of a structure enclosing said rotor and provided with a recess to receive said movable bridge and form therewith a hydraulic servo-motor for effecting movement of said movable bridge toward and from said rotor, means for supplying liquid to said servo-motor to energize the same, and a positive stop for limiting the movement of said bridge toward said rotor.

16. In a hydrodynamic machine having high and low pressure ports, a rotor, and cheek plates arranged upon opposite ends of said rotor, the combination of a recessed spacer ring arranged around said rotor to hold said cheek plates in spaced relation, a vane track arranged around said rotor and within said spaced ring and including a plurality of bridges each of which is arranged between a high pressure port and a low pressure port, two bridges constituting a pair and at least one bridge of a pair being adjustable to vary the displacement of said machine, said adjustable bridge being fitted in a recess in said spacer ring to function as a piston and having formed therein a valve bore and passages leading from said bore for the flow of liquid through said bore to and from said recess, a source of constant pressure liquid, means for supplying liquid from said source to said bore, means for supplying liquid at a pressure higher than said constant pressure to said bore in response to the pressure in said high pressure port exceeding said constant pressure, a valve fitted in said bore for controlling the flow of liquid to and from said recess, and means for adjusting said valve.

17. In a vane type hydrodynamic machine having high pressure and low pressure ports, a rotor provided with radial vane slots and a vane slidably fitted in each of said slots, the combination of an endless vane track extending around said rotor and including a plurality of sealing bridges and a plurality of working bridges each of which is arranged between a high pressure port and a low pressure port and a plurality of extensible vane track sections each of which is arranged between adjacent bridges, means for moving said working bridges toward and from said rotor to vary the displacement of said machine, each of said track sections having a concave track surface upon its inner face and each of said bridges having upon the inner face thereof a track surface which is concave intermediate its ends for a distance at least as great as the distance between the outer ends of two adjacent vanes, and posts fixed to each of said track sections at opposite ends thereof and pivotally connected to the adjacent bridges at points spaced substantial distances radially outward from said track surfaces.

18. In a vane type hydrodynamic machine having high pressure and low pressure ports, a rotor

provided with radial vane slots and a vane slidably fitted in each of said slots, the combination of an endless vane track extending around said rotor and including a plurality of sealing bridges and a plurality of working bridges each of which is arranged between a high pressure port and a low pressure port and a plurality of extensible vane track sections each of which is arranged between adjacent bridges, means for moving said working bridges toward and from said rotor to vary the displacement of said machine, each of said track sections having a concave track surface upon its inner face and each of said bridges having upon the inner face thereof a track surface which is concave intermediate its ends for a distance at least as great as the distance between the outer ends of two adjacent vanes, recesses formed in said bridges and extending a substantial distance from the inner faces of said bridges, posts fixed to each of said track sections at opposite ends thereof and extending substantial distances into said recesses, and pins carried by said bridges and extending through the outer ends of said posts to pivotally connect said track sections to said bridges.

WALTER FERRIS.
